UNITED STATES PATENT OFFICE.

FRANK STONE, OF WORCESTER, MASSACHUSETTS.

PNEUMATIC ENGINE FOR MUSICAL-INSTRUMENT ACTIONS.

SPECIFICATION forming part of Letters Patent No. 355,229, dated December 28, 1886.

Application filed September 12, 1885. Serial No. 176,961. (No model.)

To all whom it may concern:

Be it known that I, FRANK STONE, a citizen of the United States, residing at Worcester, in the county of Worcester and State of Massachusetts, have invented certain new and useful Improvements in Pneumatic Engines for Musical-Instrument Actions; and I declare the following to be a description of my said invention sufficiently full, clear, and exact to enable others skilled in the art to which it appertains to make and use the same, reference being had to the accompanying drawings, which form a part of this specification.

The objects of my present invention are to provide a practical and efficient engine for operating the mechanism of musical instruments by pneumatic force generated by the bellows-action; to provide a pneumatic engine having motors and valve mechanism constructed and disposed in a manner to give powerful action on the operated shaft, while requiring but little air for their operation, and which run with the smallest fraction of loss from waste of air and friction; to provide means for pneumatically actuating the valves which control the ingress and egress of air to and from the motors; to provide means for adjusting or regulating the valve-action so that the force of the respective motors will be exerted and relieved at the proper instant of time; to construct and combine the several parts of the mechanism with each other with a view to convenience and durability in use and in a manner that will afford facilities for economic manufacture. These objects I attain by mechanism the nature, construction, and operation of which are explained in the following description, the particular subject-matter claimed being hereinafter definitely specified.

In the drawings, Figure 1 is a front view of my pneumatic engine for musical instruments. Fig. 2 is a plan view of the same, one of the motors with its valve-actuating pneumatics being shown in horizontal section. Fig. 3 is a vertical section of the engine mechanism at the position of line α α , Fig. 1, in combination with the wind-chest and action of a mechanical musical instrument, with the arrangement of the driving-belts for operating the music-sheet, (indicated by dotted or broken lines,) and also showing the combination with

the engine, traveling music-sheet, and reed-action of a fan-tremolo driven by the engine mechanism. Fig. 4 is a diagram, on smaller scale, indicating the bellows and pedals. 55

In referring to parts, A indicates the wind-chest of the pneumatic engine, which is arranged in connection with or auxiliary to the main wind-chest A' of the musical instrument, in such manner that the air within its interior chamber can be exhausted by the action of the bellows B when the pedals b are worked, the engine being operated by the same exhausting action as that employed for sounding the reeds or playing the instrument. Said wind-chest A is in the present instance located in an upright position on the rear part of the action-board a . In some cases, however, it will be found more convenient to have said wind-chest otherwise disposed in relation to the musical action, and it may therefore be placed in any convenient relation to the main wind-chest A', its interior chamber being connected by any suitable arrangement of passages for common exhaustion of air. Said wind-chest may be a part of the main wind-chest A', or be placed in a horizontal position thereon.

C indicates a shaft arranged parallel to the front plane of the wind-chest, mounted to turn 80 in bearings, and provided with a number of cranks, c , standing at different angles in relation to each other, to which cranks the several motors are connected.

D' D² indicate a series of motors arranged 85 on the face of the wind-chest in the same plane with each other. Said motors are constructed in a manner similar to the feeders of organ-bellows, and consist of collapsible chambers with flexible sides and tops of rubber cloth or other suitable fabric, and with movable front boards hinged at the bottom edges, so that their top ends will respectively swing outward and inward as the air-pressure within the motor is varied. In the present instance three motors 95 are shown; but a greater number may be employed, if desired, all being constructed and arranged substantially similar to those herein shown. The motors are connected with the respective cranks c on the operating-shaft C by 100 means of pitman-rods, as d , pivoted or hinged to their movable ends, as indicated.

In the back of each of the motors there is a port, *e*, (see dotted lines, Fig. 1,) opening into the interior of the wind-chest *A*, and provided with a valve, *E*, within the air-chamber, and 5 also a port or passage, *f*, extending through to the exterior, and provided with a valve, *F*, on the opposite side of the wind-chest. Within the wind-chest there are arranged sets of expandable pneumatic fingers, *I* and *J*, into which 10 air-passages *i* and *j* lead from the exterior or top of the chest. (See dotted lines, Fig. 1.) The pneumatics *I* connect by means of pitman-pin *I'*, for opening the valves *F* when the pneumatic is expanded, and the valves *E* are each 15 provided with an arm and adjustable stud, *e'*, whereby they are operated from the pneumatic fingers *J*.

H and *K* indicate valves arranged upon the outside of the chest, over the ends of the air- 20 passages *i* and *j*. Said valves are connected in pairs to reciprocating bars *G*, the interval of connection being such that when one valve is opened the other is closed, and vice versa.

The reciprocating bar *G* and valves *H* and 25 *K* in each set are operated by the arm of a lever, *L*, fulcrumed, as at *l*, with its opposite arm actuated by a cam or eccentric, *C'*, on the shaft *C*. The bars *G* are provided with screw-buttons or suitable adjusting devices, *n*, where- 30 by the parts can be regulated to give the required movement at the proper instant of time.

The several valves *E* and *F* are provided with springs *E'* *F'*, to effect their closing action, and a spring, *g*, is arranged to press on 35 the bar *G*, for holding the valves *K* and *H* to their work. Springs *L'* are also provided for pressing down the levers *L* in opposition to the cam movement.

M and *m* indicate pulleys on the shaft *C* for 40 the music-working bands. Said pulleys are loose on the shaft, and are brought into action by means of a sliding clutch, *N*, that is fitted to revolve with said shaft, and which can be moved either to right or left to engage either of 45 said pulleys at will, suitable locking-lugs being employed thereon for effecting their revolution.

The musical instrument may be of any kind desired or constructed in suitable manner, and 50 the engine may be applied thereto substantially as illustrated in Fig. 3.

W denotes the band for operating the winding shaft or spool *S* for drawing forward the music-sheet, and *w'* the band for operating the 55 rewinding-spool *S'*.

The shaft *C* may be placed at any convenient position in relation to the motors *D*, it being parallel to the plane thereof, so as to be rotated by the serial connections, and the cams 60 may be of eccentric or other irregular form, such as desired, for imparting the required time and quality of movement to the valves for controlling the action of the motors. The crank-shaft having cams and employed with 65 motors *D*, arranged in the same plane and parallel therewith, may be used for operating

valves of other construction than those herein shown, or when the valve controls the inlet or exit of air direct to or from the motor *D*.

A sliding gate or valve, *X*, is provided for 70 closing the passage between the auxiliary wind-chest *A* and exhaust-chamber *A'*, and a gate or valve, *Y*, is also provided for stopping off the sounding devices from the exhaust-chamber *A* during the rewinding operation, 75 so that the bellows *B* and engine can be operated without producing sound while rewinding the music-sheet. The cut-off valve *Y* and clutch device *N* may be connected for simultaneous operation, if desired. 80

The operation of my improved mechanism is as follows, viz: The several motors and valve devices are arranged to operate in regular rotative order, so that at all times some one or more of them is in full action, exerting 85 force for revolving the shaft *C*, while the others are recovering their position. Thus, assuming that the parts are in position, as shown in Fig. 3, and the chamber *A* exhausted, the valve *H* being open, the pneumatic *I* is 90 expanded by atmospheric pressure entering passage *i*, and the exterior air-valve, *F*, is thereby held open, so that air can pass in through port *f* to fill the motor-chamber *D*. During this action the shaft *C* is being 95 revolved by the other motors *D*, which have previously been filled and are at the time in communication with the chamber *A*. When the cam *C'* arrives at a position to lift the lever *L*, the bar *G* is reciprocated, and valve *H* is 100 thereby closed and valve *K* is opened, letting in air-pressure to pneumatic *J* and stopping it off from pneumatic *I*. The former immediately expands, forcing open valve *E*, while the latter collapses and allows the valve *F* to 105 close under the action of its spring. Immediately on the shifting of the valves the exhaustion within the wind-chest *A* causes the atmospheric pressure from without to act upon the motor *D*, and the air flows therefrom to 110 the chamber *A* through port *e*, thus effecting the collapse of the motor *D*, and as the top of said motor is linked to the crank *c* the revolution of the shaft *C* and cams *C'* is consequently effected. The cam, by actuating the 115 lever *L*, again shifts the valves *H* and *K*, stopping off the pneumatic *J*, and allowing air to enter the other pneumatic, *I*, which latter immediately expands and opens the valve *F*, while the former collapses and allows the 120 valve *E* to close. The exterior air is thus again allowed to enter the motor without hinderance, and the top board is drawn out by the revolution of the crank *c*. This operation, being consecutively repeated by each of 125 the several motors *D*, which are severally arranged in the same plane with each other, revolves the shaft *C* with a continuous, steady, and powerful action, which can be varied by the moving in or out of the gate or slide valve 130 *X*, so as to give any desired degree of speed. By means of the screw-buttons or adjusting

devices *n*, the action of the small valves *H* and *K* and pneumatic fingers can be accurately regulated, so that the ports *e* and *f* will be opened and closed at the exact required instant of time and in a prompt and sufficient manner, the entire valve action being accomplished comparatively without friction.

What I claim as of my invention, and desire to secure by Letters Patent, is—

1. A pneumatic engine for musical instruments, having a series of motors (three or more) disposed laterally to each other in the same plane, in combination with a crank-shaft arranged parallel to the plane of said motors, connections linking said motors respectively to the cranks on said shaft, and pneumatically-actuated valve mechanism controlling the ingress and egress of air to said motors, substantially as set forth.
2. In a pneumatic engine for musical instruments, the combination, with a revoluble shaft, of a collapsible motor connected for imparting rotative action to said shaft and provided with inlet and exit ports, valves for controlling the ingress and egress of air to said motor, and pneumatic fingers for actuating said valves, substantially as set forth.
3. The combination of the shaft provided with offsetting cranks, a series of collapsible motor-chambers having inlet ports leading from the exterior and exit ports leading to the interior of the exhaust-chamber or wind-chest, valves for opening and closing said ports, pneumatic fingers within the exhaust-chamber, respectively connected for operating said valves, and valve devices for controlling the pneumatic action of said fingers actuated from the shaft or mechanism operated by said motors, substantially as set forth.
4. The combination, with the wind-chest *A*, and revoluble shaft *C*, having operating connections, as *d*, of the motor *D*, having the ports *e*, leading into the interior of said wind-chest, and the port *f*, extending through to the exterior of said wind-chest, the internally-disposed valve *E*, the externally-disposed valve *F*, and pneumatic actuating devices connected for operating said valves, substantially as set forth.

5. In a motor for operating the traveling music-sheet in a musical instrument, the combination, with valves for controlling the ingress and egress of air to the motor, operated by pneumatic force induced by the bellows, of valves for admitting air to the pneumatic devices, operated by mechanism in connection with the crank-shaft or motor, substantially as set forth.

6. The combination of an exhaust wind-chest, as *A*, motors arranged on the face thereof, having ports, as *e* and *f*, valves *E* and *F* for said ports, pneumatic fingers *I* and *J*, connected to work said valves, external valves, *H* and *K*, valves connecting bar *G*, lever *L*, crank-shaft *C*, cams *C'*, and pitman rods or links *d*, substantially as and for the purpose set forth.

7. The combination, with valve-operating pneumatic fingers *I* and *J*, of the valves *H* and *K*, connection-piece *G*, actuating-lever *L*, and adjusting devices *n n*, substantially as and for the purpose set forth.

8. The combination, with motors *D*, *D'*, and *D''*, crank-shaft *C*, and links *d*, of the valves *E* and *F*, pneumatic fingers *I* and *J*, connected therewith, as described, the valves *H* and *K*, bar *G*, lever *L*, cams *C'*, pulleys *M m*, bands *W W'*, spools *S S'*, and music-sheet *P*, substantially as and for the purpose set forth.

9. A pneumatic engine for musical instruments, comprising a series of motors or collapsible chambers, and provided with adjusting devices for regulating the time of action of the controlling air-valves in relation to the valve-operating mechanism and the movement of the motor, as set forth, whereby either of the motors can be caused to exert its force at an earlier or later instant in relation to the others.

Witness my hand this 29th day of August, 1885.
